ALBERT E. SPOONER,
INVENTOR.

BY Harold C. Steymann
ATTORNEY

UNITED STATES PATENT OFFICE

ALBERT EDWARD SPOONER, OF RENFREW, ONTARIO, CANADA

RAILROAD-CROSSING GATE

Application filed April 3, 1930. Serial No. 441,273.

This invention relates to railroad-crossing gates and particularly to the means for operating the same.

The object of my invention is to provide a simple, inexpensive and efficient means for operating the road portions of the gates and the pedestrian portion of the gates simultaneously.

With the foregoing and other objects in view as will appear as the description proceeds, the invention consists of the novel construction, combination and arrangement of co-operating elements as hereinafter more specifically set forth, claimed and shown in the accompanying drawings forming a part of the present application, in which:

Fig. 1 is a diagrammatical view, showing the gates in closed position with their flexible connection extending to the operating tower.

Fig. 2 is a schematic view, showing a connection between the respective operating means and the tower operating means.

Fig. 3 is a top plan view of the operating means for the gates.

Fig. 4 is a sectional view taken on the line 4-4 of Fig. 3.

Like numerals of reference designate corresponding parts throughout the different views.

A is the railroad bed, B is the roadway and C is the pedestrian path or sidewalk. E, F, G and H are housings. In the following description I have shown in Figs. 3 and 4 the housing G, the housings E, F and H being of a similar type and having corresponding operating means therein.

Each housing is an enclosure 5 with a base 6, preferably formed of reinforced concrete, steel or the like. If desirous a top may be placed thereover with suitable slots therein to permit the bars of the gates to be operated therethrough.

7 is the main shaft supported in suitable bearings on the opposite sides of the housing 5. Mounted on the shaft 7 is a sprocket gear 8 over which the sprocket chain 9 is trained. The sprocket gear 8 is keyed to the shaft 7 by means of the key 10. 11 and 12 are castings having annular openings therethrough, which castings are fitted on and keyed to the

shaft 7 at opposite sides of the sprocket gear 8. The inner ends of the side bars 14, which form part of the gate 15, are suitably bolted at their inner ends to the respective castings 11 and 12. If desirous, the castings 11 and 12 may be heavier on the inner side to act as a counterbalance weight. 16 is the pedestrian gate provided with a removable facer plate 17 on its under side adjacent its inner end. The end wall of the housing 5 is provided with a facer plate 18 over which the facer plate 17 and the pedestrian gate is adapted to be slidably moved. The inner end of the pedestrian gate is hingedly connected to the inner end of one of the side bars 14 by means of the hinge 19. The end of this side bar 14 and the end of the pedestrian gate 16 is notched to permit the cable 20 to extend up therebetween when the gates are in closed position. This cable 20 has its upper end connected around the pin of the hinge 19 and its lower end connected to the counterbalance weight 21.

22 and 23 are shafts suitably supported in bearings on the opposite sides of the housing 5. Mounted on the shaft 22 is the idler pulley 24. Mounted on the shaft 23 is the idler pulley 25. Connected to the outer end of the sprocket chain 9, I provide a flexible cable 26, which extends down and around the idler pulley 24, through a suitable opening 27 in the side of the housing G and through a conduit 28 to the tower 29. The inner end of the sprocket chain 9 has connected thereto a flexible cable 30, which extends down and around the idler pulley 25, through a suitable opening 31 in the housing G, through a suitable conduit 32 under the road bed to the housing F, around one portion of the idler pulley 33, around the sprocket gear 8^a, back around the other portion of the idler pulley 33, back through the conduit 32, through the housing G, through the conduit 28, up to the tower 29, around the operating drum 34 in the tower and has its end connected to the flexible cable 26 to form an endless interconnecting flexible control member between the sprocket gears 8, 8^a and the operating drum 34. The flexible cable 30, where it passes around the sprocket gear 8^a, 100

will be provided with a sprocket chain similar to the sprocket chain 9, so as to transmit positive rotary movement to the sprocket gear 8^a. The housings E and H are provided with similar operating means and an endless interconnecting flexible control member 26^a for operating the same, which is trained over a drum 34^a corresponding to the drum 34 in the tower 29. Thus, the gates operating from the housings E and H will be controlled by one drum, while the gates operated from the housings F and G will be controlled separately by another drum.

The foregoing specification and annexed drawings disclose the preferred embodiment of my invention, but it is to be understood that minor changes may be resorted to in the commercial adaptation of my invention without departing from the scope of the invention as hereinafter claimed.

What I claim as new is:

A railroad-crossing gate comprising a set of four housings, one positioned at each respective corner of the intersection between a roadway and a railroad bed; each of said housings comprising side walls, end walls and a base; each of said housings having a shaft suitably mounted in bearings supported in the side walls of said housing; an operating gear keyed on said shaft; counterbalance weights keyed on said shaft; road gates; the ends of the side bars of said road gates being connected to said counterbalance weights; a pedestrian gate, having a facer plate on its under side adjacent its inner end; a facer plate on the top of the end wall over which said pedestrian gate facer plate is adapted to move; the end of said pedestrian gate being hingedly connected to the end of one of the side bars of said road gate; a counterbalance weight suspended from the pin of said hinge; flexible connections between the respective gears in the housings on one side of the road with the gears in the respective housings on the opposite side of the road and said respective flexible connections being trained over separate operating means, in an operating tower, for operating said connections.

In testimony whereof, I affix my signature.
ALBERT EDWARD SPOONER.
